LOUIS W. DOWNES, OF PROVIDENCE, RHODE ISLAND.

APPARATUS FOR APPLYING INSULATION TO ELECTRICAL CONDUCTORS.

No. 878,617.

Specification of Letters Patent.

Patented Feb 11, 1906.

Application filed June 15, 1905. Serial No. 265,389.

To all whom it may concern:

Be it known that I, LOUIS W. DOWNES, of Providence, Rhode Island, have invented a new and useful Improvement in Apparatus for Applying Insulation to Electrical Conductors, which invention is fully set forth in the following specification.

This invention consists of improved apparatus for applying fibrous insulating material—particularly asbestos—to the surface of an electric conductor or wire by spirally wrapping or winding said material on the wire. The difficulties of applying asbestos fiber to a wire in a loose, straightened, un-twisted condition are well known. Such asbestos fiber can be procured in the market in the form of silver, or "roving", as it is better known to the trade. In this and analogous forms there is little coherence between the individual fibers and they pull apart and break under slight strain. For these reasons it has been the usual practice to employ asbestos in the form of yarn, which is asbestos sliver twisted to give it greater tensile strength. While asbestos yarn may be more readily handled in the act of applying it to the wire, it presents little advantage after it is on the conductor. There are some disadvantages; the natural lumpiness of asbestos is more apparent in the yarn than in the fiber in an un-twisted, straightened or carded state. When applied in an un-twisted, straightened condition the fibers adhere to the wire in a loose, fluffy or flocculent condition, enabling them to be readily compacted into an even layer, for which reason the subsequent finishing operations can be more effectively carried out; and furthermore, not only is the un-twisted, straightened fiber less expensive than the yarn, but it can, with proper apparatus, be applied in minimum quantity, producing an insulating covering of minimum thickness, if desired.

I am aware that it has heretofore been proposed to wrap un-twisted, carded asbestos about a wire by causing the wire, instead of the asbestos, to rotate, but this method is seriously objectionable, if not impracticable, particularly in covering heavy and very fine conductors; in the case of heavy conductors it necessitates the rapid rotation of heavy masses of metal, which is a difficult and dangerous operation; in the case of fine or

very small conductors there is great danger of twisting and breaking the wire. In my pending applications for Letters Patent Sr. No. 215,694 and Sr. No. 215,695, both filed July 7, 1904, I have disclosed apparatus for applying un-twisted straightened asbestos fiber to a non-rotating wire, wherein the asbestos is drawn from a source of supply—receptacle, spool or cop—mounted on and rotating with the carrier. According to my present invention, which embraces apparatus embodying the generic invention of my said application Sr. No. 215,694, the source of supply of the fiber is not on the carrier, but is relatively fixed contiguous thereto and delivers the fiber to the operating parts on the carrier as the latter rotates, thereby avoiding stoppages necessary to charge the receptacle or replace the spools or cops. Other objects of the invention will be apparent from the description which follows; among these may be mentioned applying to the wire a uniform layer of straightened un-twisted fiber, the machine being adapted to vary the layer to a minimum thickness and to operate upon wires of different sizes and thereby especially adapted to the production of so-called "magnet-wire".

In the accompanying drawings illustrating several embodiments of the invention:—Figure 1 is a front elevation, with parts in section; Fig. 2 is a side elevation; Fig. 3 is a top plan view with portions of some of the parts broken away and omitted; Fig. 4 is a horizontal sectional view on line 4—4, Fig. 1, through parts mounted on the carrier, a portion of the circular plate or carrier being broken away to show parts mounted and operating on the under-side thereof; Fig. 5 is a detail vertical sectional view taken on line 5—5 of Figs. 3 and 4; Fig. 6 is a detail perspective of a bearing block which is adjustably mounted on the carrier; Fig. 7 is an enlarged plan view (with parts in section) of the mechanism for delivering the fiber to the card-wheel; Fig. 8 is a vertical section on line 8—8 of Fig. 7; Fig. 9 shows in detail parts of the fiber feeding mechanism; Fig. 10 is a vertical sectional view through the rotary carrier and some of its associated mechanism; and Fig. 11 is a plan and Fig. 12 an elevation showing a modification of parts of the mechanism.

Referring first to Figs. 1, 2 and 3, pulley

15 driven from a suitable source of power, carries a bevel gear 16 meshing with a similar gear 17 on a vertical shaft 18. A handle 19 at the upper end of this shaft serves to turn 5 the parts of the machine to any desired position when the power driving means are disconnected. A worm 20 on shaft 18 drives a worm-wheel 21 on a shaft 22; gear-wheel 23 on said shaft meshes with a gear-wheel 24 on 10 a shaft 25, and a pinion 26 on the latter shaft meshes with large gear 27 journaled on a shaft 28 supported between arms 29, 29 of the framework. A drum or sheave 30 secured on the hub of gear 27 is slowly rotated through 15 the gearing above described. The electric conductor or wire 31 passes upward through a pot 32, containing a liquid or semi-liquid adhesive material (preferably shellac) through a rotary carrier 33 where the 20 fibrous material is applied, through a guide 34 mounted on the carrier, and then several times around drum 30, rotation of which slowly draws the wire through the machine. From the drum the wire covered with fiber 25 (preferably asbestos) in a fluffy, flocculent carded state, may pass to any suitable finishing apparatus, such, for example, as shown in my Patents Nos. 534,785, dated February 26, 1895, and 709,001, dated September 16, 30 1902.

The carrier 33 is rotated by gear 35 on shaft 18, meshing with a gear 36 which latter in turn meshes with a gear 37. Gear 37 is fast on a hollow shaft 38 (see particularly Fig. 35 10) having a reduced and exteriorly screw-threaded upper end projecting through a screw-threaded opening in carrier 33; a nut 39 turned down tightly against the upper surface of the carrier tightly clamps the same 40 to the shaft. The opening through the hollow shaft is of such diameter as to permit large sizes of wire to freely pass upward therethrough. A cap-nut 40 which may be changed for different sizes of wires, is 45 screwed onto the extremity of shaft 38 above nut 39; said cap-nut has a tapering opening, the smallest diameter of which is just sufficient to permit free passage of the wire. It follows that between cap-nut 40 50 and guide 34, where the fibrous covering is applied, the wire can have little if any lateral movement. 41 is a hollow worm having a flange through which screws pass to fix it to the bracket or bridge piece 42 of the 55 framework. A short hub 43 cast on the underside of carrier 33 rests against and turns upon the upper edge of hollow worm 41, while hollow shaft 38 passes through said worm. This worm imparts movement to 60 parts on the carrier during rotation of the latter, as will now be more fully explained.

Referring particularly to Figs. 4, 5 and 6, shaft 45 is journaled in a depending bearing 45^a secured to the underside of carrier 33. 65 A worm-wheel 46 secured to the inner end of

said shaft meshes with the fixed worm 41, whereby the shaft is slowly rotated in its bearings as the carrier 33 rotates about the wire. 47 is an adjustable bearing block located beneath the carrier, but having a vertical boss 48 which projects upward through a slot 49 in the carrier (see Figs. 3 and 4). A rib 50 on the bearing block also engages an elongated opening 51 (Figs. 4 and 5) in the carrier and serves to guide the block in its 70 movement of adjustment which may be effected by turning a bolt 52 passing through a bracket 53 (fixed to the underside of the carrier, Fig. 4) and engaging a screw-threaded socket 54 in the bearing block 47. Bolts 55 and 56 passing through slots in carrier 33, serve to rigidly clamp the block in the position to which it is adjusted by bolt 52. A short shaft 57, supported in bearing 58 of block 47, carries at its outer end a gear 59, 80 and at its inner end a spiral gear 60. Gear 59 meshes with and is rotated by a gear 61 on the outer end of shaft 45. The carrier 33 is bulged upwardly at its edge on one side, as clearly shown in Figs. 2 and 3, to accommodate 85 these gears 59 and 61 and provide space for the substitution of gears of different relative sizes. The spiral gear 60 drives a spiral gear 63 on the lower end of a vertical shaft 64 which latter passes upward through boss 48 90 and carries the card-wheel 65. Said wheel is securely clamped against a shoulder on the shaft by a nut 66 engaging a screw-threaded portion of the shaft. The upper reduced end of shaft 64 bears in and is steadied by a 100 bracket arm 67 adjustably secured to the carrier 33 by a bolt 68 passing through a slot 69 in said arm. The card wheel shown in the drawing and as preferably formed, consists of a pulley covered with suitable card clothing, shown in transverse section in Figs. 1 and 5, and the teeth of which may or may 105 not be inclined.

Referring now to the mechanism for feeding the fiber to position to be picked up by the card-wheel as the latter is carried around by the carrier 33, 70 is a pulley on shaft 22 driving a pulley 72 through a belt 71. Pulley 72 is fast on a shaft 73 journaled on the under side of a table 74 which latter overhangs the 115 edge of the carrier 33 slightly below the level of card-wheel 65. A ribbed feed roller 82 on a shaft 81 is slowly rotated through the following connections: A worm 75 on shaft 73, worm-wheel 76 on a shaft 77, gear 78 on said shaft, intermediate gear 79 meshing with gear 80 on shaft 81. 83 and 84 are two cops or spools supported respectively upon bracket-arms 85 and 86. The fiber, preferably in the form of sliver, or "roving", as it is 120 commonly known, passes through two funnel-like guide openings 87 and 88 in a bracket 89, and thence between the roller 82 and a spring-metal plate 90. The latter is pivoted on a pin 91 at one end at its other end held 130

in the desired proximity to the feed roller 82 by a screw 92. The parts are so adjusted that the pressure of plate 90 and roller 82 flattens the two or more rovings of fiber and 5 delivers them in the form of a sheet of carded or partially carded and straightened un-twisted fibers almost the width of the periphery of the card-wheel. The feed-roller 82 advances the sheet of fiber across the toothed 10 edge of a blade 93, where the projecting fiber is caught by the teeth of the card-wheel 65 as it intermittently passes, once for each rotation of the carrier. The card-teeth draw out and separate the fibers against the 15 surface of the shoe or breaker 94, which is preferably of leather so as to present a somewhat soft surface, avoiding injury to the card teeth and retarding the movement of the fibers so that they will be further drawn 20 out and straightened, if necessary. The straightened carded and loosely separated fibers are finally picked up and carried away in the card-teeth, as shown in Fig. 7. Shoe 94 is supported by a plate 95 (Figs. 7 and 8) 25 to which it is secured in any suitable manner. Toothed blade 93 is also supported by said plate, being secured thereto by screws 96 which pass through an intermediate block 97. Plate 95 is adjustably secured to table 30 74 by set-screws 98 passing through slots 99 in arm 100. Adjusting screw 92 heretofore mentioned, passes through an ear 101 on arm 100.

In the operation of the machine of Figs. 1 to 10, the carrier 33 rapidly rotated (in the direction of the arrows, Figs. 3 and 4) by the driving connections described, carries with it the card-wheel 65, the latter being at the same time slowly rotated on its axis in 40 the direction of the arrows by the gearing operated from the fixed worm 41. On each rotation of the carrier the card-wheel, positioned eccentric to the axis of the carrier, sweeps by the fiber delivering mechanism 45 and picks up a quantity of fibers depending upon the rapidity of feed by the feeding mechanism, the position of the card wheel being constantly changed by its rotation on its axis. It follows that there is a gradual 50 accumulation of fibers in the teeth of the card-wheel, forming in said teeth a uniform layer of evenly distributed loose, straightened and carded fibers, said layer extending at all times part way around the periphery 55 of the card wheel, as shown in Fig. 3. The connections for rotating card-wheel 65 are so proportioned that the surface speed of the card-wheel due to its rotation on its axis is approximately the same as the speed of 60 movement of the carrier and the card-wheel with relation to the circumference of the wire due to the rotation of the carrier. In other words, the card-wheel and the wire have a movement analogous to a "sun and planet 65 motion," the card-wheel representing the

planetary element. The effect produced is an unwinding of the fibrous layer or band from the surface of the card-wheel onto the sticky surface of the longitudinally moving wire at the point where the teeth of the card-wheel closely approach said wire, the action of the wire in thus licking up the fibers from the card-surface being somewhat analogous to the action of the doffer which removes the carded material from the card rolls in a carding machine. But preferably the surface speed of the card-wheel is slightly less than the speed of revolution of said wheel about the wire, whereby there is a slight pulling and consequently a further stretching and straightening of any unstraightened fibers as they pass from the card-teeth onto the wire. To obtain the desired surface speed of card-wheel 65 for large sizes of wires it is necessary to rotate said wheel at higher 70 speed than for small sizes of wires. The desired speed of rotation may be obtained by replacing gears 59 and 61 by others of appropriate sizes according to the particular size of wire being covered. Furthermore, since 75 the card-teeth on wheel 65 must almost touch the surface of the wire, it becomes desirable, in order to avoid the necessity of different sized card-wheels for different sizes of wires, to adjust the position of the card-wheel and its driving connections to the particular size of wire being covered. To change the position of the card-wheel, bolts 55, 56 and 68 are loosened, and the adjusting 80 bolt 52 turned. This will move the bearing block 47 and the parts mounted thereon and connected thereto, including the card-wheel and the bracket 67. The gear 59 will be moved relative to the fixed gear 61, as indicated by dotted lines, Fig. 4, but the teeth of 85 these gears are of sufficient width to permit of the desired range of adjustment without throwing said gears out of mesh. The speed of operation of the feed-roller 82, and consequently the rapidity of feed of the fibrous 90 material and thickness of the fibrous covering applied to the wire, may be altered by substituting for gears 78, 79 and 80 others of different relative sizes. Furthermore, the relative speed of the longitudinal movement 95 of the wire may be varied as desired by changing the gears 23 and 24.

Referring now to the modified structure shown in Figs. 11 and 12, it is to be understood that parts of the machine not shown in these figures may be the same as shown in Figs. 1 to 10. Rotary carrier 110 is secured to the upper end of hollow shaft 111 by a nut 112, and rotated by suitable connections to a gear 113 on the shaft. All of the parts 120 mounted on and rotating with the carrier are driven by suitable connections from fixed bevel gear 114 and fixed gear 115, both cast on a hub 116. Screws 117 (dotted lines, Fig. 12) pass downwardly through said hub 125 130

and secure it to bushing 118 fixed in an opening through a part 119 of the frame of the machine. 120, 121, and 122 are card-wheels (the card clothing on the surface thereof being shown only in section in Fig. 12) secured respectively on shafts 123, 124 and 125, all of which shafts pass through bearings in the carrier and project below the latter. All of these card-wheels are positioned eccentric to the axis of the carrier. Card-wheel 121 is rotated on its axis during rotation of the carrier, by gear 126 (on stud 127) meshing with fixed gear 115 and in turn driving gear 128 fixed on shaft 124 below the carrier. 15 Card-wheel 122 is driven through the following connections all below the carrier: bevel gear 129 meshes with fixed bevel gear 114, and drives shaft 130 journaled in bearings secured to the underside of the carrier. A 20 worm 131 on said shaft drives a worm-wheel 132 on stud 133; gear 134 secured to the hub of worm-wheel 132 drives gear 135 which in turn drives gear 136 on shaft 125. Gear 135 rotates on a stud 137. Gear 136 communicates rotary movement to card-wheel 120 through the following gearing: gear 138 on a stud 139, gear 140 on stud 141, sprocket 142 secured to the hub of gear 140, sprocket chain 143 and sprocket 144 on shaft 123. 25 To permit card-wheel 122 to be moved towards or from the axis of rotation of the carrier in adjusting the mechanism to the covering of different sizes of wires, the studs 137 and 139 and shaft 125 may be adjusted in 30 slots 143^a in the carrier.

Referring now to the means for delivering fiber to the carrier, 150 is a cop or spool mounted upon a table at one side of the carrier. The fibrous material, preferably asbestos in the form of roving, passes over an upright feed plate against which it is gripped and advanced by a ribbed roller 152. The latter is intermittently rotated by gear 153 meshing with gear 154 on shaft 157 carrying 40 a star wheel 155, the latter being actuated by a pin 156 on carrier 110.

The operation of the mechanism of Figs. 11 and 12 is analogous to that of the other figures and requires but little additional explanation. The fibers picked up by the teeth of card-wheel 120 each time it sweeps by the feed-plate 151, are removed from said card-wheel by the teeth of card-wheel 121, from which latter they are in turn picked up 50 by the teeth of card-wheel 122 and delivered thereby into contact with the sticky surface of the wire carded and straightened into a uniform layer. The gearing for rotating the card-wheels on their axes is so arranged and 55 proportioned as to impart to said wheels different surface speeds. For example, by rotating card-wheel 121 forty revolutions per minute, card-wheel 120 eighteen and two-thirds revolutions per minute, and card-wheel 122 eight revolutions per minute, a 60

very effective relation of surface speeds is obtained. The surface speed of wheel 121 being much faster, its teeth draw out the fibers which are picked up from the teeth of the slower moving wheel 120. This drawing out of the fibers is repeated as the teeth of the slower moving card-wheel 122 pick them up from the teeth of wheel 121. As the surface speed of wheel 122 due to its rotation on its axis preferably approximates the speed of movement of the card-wheel with relation to the circumference of the wire due to rotation of the carrier, the effect produced is to spirally wind the fibrous layer onto the longitudinally moving wire as the card wheel 122 70 rolls about the circumference of the wire, the sticky surface of the latter licking up the fibers from the teeth of said card-wheel. 75

As will be apparent, the invention is not restricted to the particular form and details of apparatus herein described and illustrated. Furthermore, changes in the relation and arrangement of the various parts may be made without departing from the nature and principle of the invention; for example, two 80 or even more fiber-feed mechanisms may be employed, suitably spaced about the rotating carrier.

The invention may, of course, be employed in applying fiber other than asbestos and for 85 covering wire used for purposes other than conducting electric currents.

What I claim is: -

1. In an apparatus for applying fibrous insulating material to a conductor or wire, a 100 carrier and means for rotating the same about the wire, means mounted upon and movable on the carrier during rotation thereof for applying fiber to the surface of the wire during rotation of the carrier about the wire, and means apart from the carrier for delivering fiber to the fiber-applying means on the carrier while the latter is in motion.

2. In apparatus for applying fibrous insulating material to a conductor or wire, a carrier and means for rotating the same about the wire, means mounted on the carrier for applying fiber to the surface of the wire during rotation of the carrier about the wire, and means apart from the carrier for delivering fiber into position to be picked up by the fiber-applying means on the carrier while the latter is in motion.

3. In apparatus for applying fibrous insulating material to a conductor or wire, a carrier and means for rotating the same about the wire, means mounted upon and movable on the carrier during rotation thereof for applying a layer of loose straightened fiber to the surface of the wire during rotation of the carrier about the wire, and means apart from the carrier for delivering fiber to the fiber-applying means on the carrier while the latter is in motion.

4. In apparatus for applying fibrous insu- 130

lating material to a conductor or wire, a carrier and means for rotating the same about the wire, means mounted on bearings on the carrier for applying fiber to the surface of the wire during rotation of the carrier about the wire, driving connections for operating said fiber-applying means on said bearings to advance fibrous material to the surface of the wire during rotation of the carrier, and 5 means apart from the carrier for delivering fiber to the fiber-applying means on the carrier while the latter is in motion.

5. In apparatus for applying fibrous insulating material to a conductor or wire, a carrier and means for rotating the same about the wire, means mounted on bearings on the carrier for applying a layer of loose straightened fiber to the surface of the wire during rotation of the carrier about the wire, 15 driving connections for operating said fiber-applying means on said bearings to advance the layer of fibrous material to the surface of the wire during rotation of the carrier, and means apart from the carrier for delivering fiber to the fiber-applying means on the carrier while the latter is in motion.

6. In apparatus for applying fibrous insulating material to a conductor or wire, a carrier and means for rotating the same about the wire, means mounted on bearings on the carrier for applying a layer of loose straightened fiber to the surface of the wire during rotation of the carrier about the wire, driving connections for operating said fiber-applying means on said bearings to continuously advance the layer of fibrous material to the surface of the wire during rotation of the carrier, and means apart from the carrier for delivering fiber to the fiber-applying means on the carrier while the latter is in motion.

7. In apparatus for applying fibrous insulating material to a conductor or wire, means for feeding the wire longitudinally, a carrier and means for rotating the same about the longitudinally moving wire, means mounted upon and movable on the carrier during rotation thereof for applying a layer of loose straightened fiber to the surface of the wire during rotation of the carrier about the wire, and means apart from the carrier for delivering fiber to the fiber-applying means on the carrier while the latter is in motion.

55 8. In apparatus for applying fibrous insulating material to a conductor or wire, a carrier and means for rotating the same about the wire, carding means mounted on the carrier for applying fiber to the surface of the wire during rotation of the carrier, and means apart from the carrier for delivering fiber to said carding means while the carrier is in motion.

9. In apparatus for applying fibrous in-

sulating material to a conductor or wire, a carrier and means for rotating the same about the wire, carding means mounted on the carrier for applying fiber to the surface of the wire during rotation of the carrier, driving connections for operating the carding means to advance the fiber to the wire during rotation of the carrier, and means apart from the carrier for delivering fiber to the carding means while the carrier is in motion.

10. In apparatus for applying fibrous insulating material to a conductor or wire, a carrier and means for rotating the same about the wire, carding means eccentrically positioned on the carrier for applying a covering of loose straightened fiber to the surface of the wire during rotation of the carrier, driving connections for operating the carding means to advance the fiber to the wire during rotation of the carrier, and means apart from the carrier but in the path of the eccentrically positioned carding means for delivering fiber to said carding means while the carrier is in motion.

11. In apparatus for applying fibrous insulating material to a conductor or wire, a carrier and means for rotating the same about the wire, means on the carrier for applying fibrous material to the surface of the wire, said means being adjustable to different positions for different sizes of wire, and driving connections for operating the fibrous material applying means during rotation of the carrier.

12. In apparatus for applying fibrous insulating material to a conductor or wire, a carrier and means for rotating the same about the wire, means on the carrier for applying a layer of loose straightened fiber to the surface of the wire, said means being adjustable to different positions for different sizes of wire, and driving connections for operating the fiber applying means during rotation of the carrier.

13. In apparatus for applying fibrous insulating material to a conductor or wire, a carrier and means for rotating the same about the wire, means on the carrier for applying a layer of loose straightened fiber to the surface of the wire during rotation of the carrier, driving connections for operating the fiber-applying means while the carrier is in motion, and adjusting means for changing the position of said fiber-applying means and its driving connections for different sizes of wire.

14. In apparatus for applying fibrous insulating material to a conductor or wire, a carrier and means for rotating the same about the wire, means on the carrier for applying a layer of loose straightened fiber to the surface of the wire during rotation of the carrier, driving connections for operating the fiber-applying means while the carrier is in

6 motion, adjusting means for changing the position of said fiber-applying means and its driving connections for different sizes of wire, and means apart from the carrier for delivering fiber to the fiber-applying means on the carrier while the latter is in motion.

15. In apparatus for applying fibrous insulating material to a conductor or wire, a carrier and means for rotating the same about the wire, fiber-carding means on the carrier for applying loose straightened fiber to the surface of the wire, said carding means being adjustable to different sizes of wire, and driving connections for operating the carding means during rotation of the carrier.

16. In apparatus for applying fibrous insulating material to a conductor or wire, a carrier and means for rotating the same about the wire, fiber-carding means on the carrier for applying loose straightened fiber to the surface of the wire, said carding means being adjustable to different sizes of wire, driving connections for operating the carding means during rotation of the carrier, and means apart from the carrier for delivering fiber to the carding means while the carrier is in motion.

17. In apparatus for applying fibrous insulating material to a conductor or wire, a carrier and means for rotating the same about the wire, a card-wheel mounted on the carrier for applying fiber to the surface of the wire, and driving connections for rotating said card-wheel on its axis during rotation of the carrier.

18. In apparatus for applying fibrous insulating material to the surface of a conductor or wire, a carrier and means for rotating the same about the wire, a card-wheel mounted on the carrier for applying fiber to the surface of the wire, and driving connections for rotating said wheel on its axis during rotation of the carrier and in the same direction as said carrier rotates at a surface speed approximating the speed of movement of the carrier with relation to the surface of the wire due to rotation of said carrier.

19. In apparatus for applying fibrous insulating material to the surface of a conductor or wire, a carrier and means for rotating the same about the wire, means for moving the wire longitudinally, a card-wheel on the carrier for applying fiber to the surface of the longitudinally moving wire, and driving connections for rotating said wheel on its axis during rotation of the carrier and in the same direction as said carrier rotates at a surface speed approximating the speed of movement of the carrier with relation to the surface of the wire due to rotation of said carrier.

20. In apparatus for applying fibrous in-

sulating material to the surface of a conductor or wire, a carrier and means for rotating the same about the wire, a card-wheel mounted on the carrier for applying fiber to the surface of the wire, driving connections for rotating said wheel on its axis during rotation of the carrier and in the same direction as said carrier rotates at a surface speed approximating the speed of movement of the carrier with relation to the surface of the wire due to rotation of said carrier, and means apart from the carrier for delivering fiber to the carding means thereon while the carrier is in motion.

21. In apparatus for applying fibrous insulating material to a conductor or wire, a carrier and means for rotating the same about the wire, a card wheel eccentrically mounted on the carrier for applying a layer of loose straightened fiber to the surface of the wire, driving connections rotating said card-wheel on its axis during movement of the carrier to advance the fiber to the wire, said rotation of the card-wheel being in the same direction as the rotation of the carrier and at a surface speed approximating the speed of movement of the carrier with relation to the surface of the wire, and means apart from the carrier but in the path of the mechanism thereon for delivering fiber thereto while the carrier is in motion.

22. In apparatus of the character described, the combination with a carrier and means for rotating the same about the wire, of carding means on the carrier and driving connections for operating the same to apply fiber to the wire during rotation of the carrier, and fiber feeding means apart from the carrier but in the path of the carding means for delivering fiber to the latter while the carrier is in motion, said feeding means having a feed roller and means for operating the same.

23. In apparatus of the character described, the combination with a carrier and means for rotating the same about the wire, of carding means on the carrier and driving connections for operating the same to apply fiber to the wire during rotation of the carrier, and fiber feeding means apart from the carrier but in the path of the carding means for delivering fiber to the latter while the carrier is in motion, said feeding means having a shoe or breaker against which the carding means act to pick up fiber in passing the feeding means.

24. In apparatus of the character described, the combination with a carrier and means for rotating the same about the wire, of carding means on the carrier and driving connections for operating the same to apply fiber to the wire during rotation of the carrier, and fiber feeding means apart from

the carrier but in the path of the carding means for delivering fiber to the latter while the carrier is in motion, said feeding means having a leather shoe or breaker against which teeth of the carding means act to pick up fiber in passing the feeding means.

In testimony whereof I have signed this

specification in the presence of two subscribing witnesses.

LOUIS W. DOWNES.
